UNITED STATES PATENT OFFICE.

JOSEPH ERNEST COLAS AND EDMOND LOUIS MARIE RAGONOT, OF PARIS, FRANCE.

BRUSH FOR ELECTRIC CONTACTS.

1,109,899.

Specification of Letters Patent.

Patented Sept. 8, 1914.

Application filed November 1, 1913. Serial No. 798,733.

To all whom it may concern:

Be it known that we, JOSEPH ERNEST COLAS and EDMOND LOUIS MARIE RAGONOT, residing at 51 Rue Lacordaire, Paris, France, 5 have invented new and useful Improvements in or Relating to Brushes for Electric Contacts.

This invention relates to improvements in contacts intended for the intermittent closing of electric circuits, the improvements being more particularly applicable to contacts which, in use, become covered with an insulating layer, as is the case for instance with contacts arranged on railway lines.

15 A feature of the invention is the construction of a movable brush device which can constitute one of the two contacts intended to close a circuit and always enables the contact with which the brush co-operates, to 20 be maintained in a conducting condition.

The apparatus comprises a box, either closed or open, in which a brush can oscillate, mounted on a pivot pin and constantly brought back to its normal position by suitable springs. The brush is formed of metal 25 filaments held in place without welding, so as to render possible the introduction of a greasy material between the various filaments.

30 The accompanying drawing shows by way of example a construction according to this invention.

Figure 1 is a section on line *a b c d* of Fig. 2. Fig. 2 is a section on line *e—f* of 35 Fig. 1. Figs. 3 and 4 show the brush proper, respectively in elevation and in plan, and Figs. 5 and 6 show constructional details of the latter.

The same reference numerals designate 40 the same parts throughout the drawings.

1 is a rigid frame with bearings for the journals 2 of a spindle 3 which carries the brush 4 on a hollow screwthreaded rod 5. An adjustable nut 4 enables the height of 45 the brush to be regulated as the filaments wear out, and in accordance with the height of the contact with which it co-operates. Springs 7 adjustable at will by means of threaded rods 8, react on lugs 9 provided on 50 the spindle 3 and tend constantly to bring the brush into the vertical position and to insure good frictional contact. The rigid frame 1 is made in two parts connected together by bolts 10 and terminating if de-

sired in two flanges 11 which can be secured 55 to the vehicle or to the movable part which carries them. To the frame 1 rigid walls 12 can be secured constituting a protecting box provided with a cover 13, either hinged, or movable in some other manner. These walls 60 can be inclined at 14 as shown in Fig. 1, in the direction opposite to that of the traveling of the movable part, in order to allow for the inclination of the brush. The screw-threaded rod 5 which is hollow, is used for 65 lubricating. It carries a Stauffer lubricator or an oil tank 15 intended to supply the brush with oil, as will be hereinafter explained.

The brush proper is formed in the following manner (Figs. 3 and 4). The screw-threaded rod 5 supporting the brush, is provided inside with a conduit 16 communicating with the lubricator 15 connected in the usual manner to the rod. The rod is 70 held, as previously explained, at the desired height on the spindle 3 by means of the nut 6. The pin 17 prevents the screwthreaded rod 5 from turning relatively to the spindle 3. The rod is in one piece with the 75 disk 18 connected by screws 19 to a disk 20 which is recessed and is provided with holes 21 as shown in Figs. 5 and 6, into which are introduced wires 22 forming the 80 elements of the brush. These wires are held 85 in place by simply turning over their upper ends (see the enlarged scale view in Fig. 6). The wires are grouped in each hole so as to leave in the center a recess 23 into which a 90 wedge can be introduced for locking the wires. The lubricant or lubricating liquid passes through all the interstices left free 95 between the wires themselves, as well as between the wires and the wedge, in order to descend along the different filaments and 100 thus reach the contact to be brushed. The filaments are held in place by tightening the disk 18 provided with a projecting portion which enters the recess of the hollow disk 20. This results in the disk 18 pressing all 105 the folded ends of filaments against the bottom of the recess in the disk 20.

Other methods of securing can be employed, or the tightening of the two disks 18 and 20 can be effected in some other manner, 110 for instance by screwing the disk 18 directly on to the disk 20, but the described means are simpler.

Having now particularly described and ascertained the nature of our said invention, and in what manner the same is to be performed, we declare that what we claim is:—

- 5 1. A contact brush holder comprising in combination with a brush consisting of a plurality of conductive filaments, a supporting frame, an element holding the brush and pivotally mounted in said supporting frame and means connected with the brush holder for supplying a lubricant to the entire space between the various conductive filaments.
- 10 2. A contact brush holding device comprising in combination with a brush consisting of conductive filaments, a frame, a supporting element pivotally mounted in the frame, a plurality of springs connected with the sides of the frame and with said supporting element, the brush being axially adjustable in the supporting element and means for supplying a lubricant to the interspace between the filaments.
- 15 3. A contact brush holding device comprising in combination with a brush consisting of a plurality of conductive elements, a frame, a supporting element pivotally mounted in said frame, a threaded member connected with the brush and extending through said pivotal supporting element, a receptacle containing a lubricant on said threaded member, said threaded member being provided with a bore communi-

cating with said receptacle and terminating above the brush.

4. A contact brush holding device comprising in combination with a brush consisting of a plurality of electric filaments, a frame, a supporting element for the brush pivotally mounted in said frame, a member connected with the brush and extending adjustably through the pivotal support, said member being provided with a bore and means for feeding a lubricant into said bore.

5. A contact brush holding device comprising in combination with a brush consisting of a plurality of filaments, a frame, a supporting element for the brush pivotally mounted in said frame, springs detachably connected with the frame and with said supporting element, a threaded member provided with a bore connected with the brush and extending through said supporting element and a lubricant receptacle mounted on said threaded member and adapted to supply a lubricant through the bore of said threaded member to the elements of the brush.

Dated this 9th day of October 1913.

In testimony whereof we affix our signatures in presence of two witnesses.

JOSEPH ERNEST COLAS.

EDMOND LOUIS MARIE RAGONOT.
